[57] CLAIM

The ornamental design of a railing planter box holder, as shown and described.

DESCRIPTION

FIG. 1 is a perspective view of a railing planter box holder showing my new design;

FIG. 2 is a right side elevation view thereof, the left side elevation view thereof being a mirror image;

FIG. 3 is a top plan view thereof;

FIG. 4 is a front elevation view thereof;

FIG. 5 is a bottom plan view thereof;

FIG. 6 is a rear elevation view thereof; and,

FIG. 7 is a perspective view thereof showing an alternate embodiment.
